US00D619367S

(12) United States Design Patent
Zhang

(10) Patent No.: US D619,367 S
(45) Date of Patent: * Jul. 13, 2010

(54) HANDHELD DEVICE FOR CARRYING BAGS

(75) Inventor: Binhui Zhang, Ningbo (CN)

(73) Assignee: Beifa Group Co., Ltd., Ningbo (CN)

() Term: 14 Years

(21) Appl. No.: 29/337,297

(22) Filed: May 19, 2009

(30) Foreign Application Priority Data

Nov. 20, 2008 (CN) 2008 3 0269855

(51) LOC (9) Cl. 03-99

(52) U.S. Cl. D3/328
